UNITED STATES PATENT OFFICE.

MAYO E. ROE, OF ELYRIA, OHIO.

DESIGN FOR A BICYCLE.

Application filed January 2, 1926. Serial No. 15,944. Term of patent 7 years.

To all whom it may concern:

Be it known that I, Mayo E. Roe, a citizen of the United States, residing at Elyria, in the county of Lorain and State of Ohio, have invented a new, original, and ornamental Design for Bicycles, of which the following is a specification, reference being had to the accompanying drawing, forming part thereof.

The figure is an elevational view of a bicycle showing my new design.

I claim:

The ornamental design for a bicycle, as shown.

In testimony whereof, I hereunto affix my signature this 24th day of December, 1925.

MAYO E. ROE.
